UNITED STATES PATENT OFFICE.

ELMER L. SCHUMACHER, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

OPHTHALMIC MOUNTING.

Application filed September 5, 1919. Serial No. 321,928.

To all whom it may concern:

Be it known that I, ELMER L. SCHUMACHER, a citizen of the United States, residing at Southbridge, in the county of 5 Worcester and State of Massachusetts, have invented certain new and useful Improvements in Ophthalmic Mountings, of which the following is a specification.

This invention relates to improvements in 10 ophthalmic mountings, and has particular reference to a mounting comprising both metallic and non-metallic portions.

Previous to the present invention mountings of this general character have been produced in a number of ways, including the securing of sheet, grooved or other non-metallic stock, to metallic parts of mountings, as by rivets, screws, clamps or other forms of fastening devices, while in addition attempts have been made to produce a 15 structure of this character by taking a regular frame and dipping or coating it with a film of liquid celluloid or the like. The metallic fastening devices have possessed considerable disadvantage due to their appearance, to the weakening of the material by the application of the securing device, and the like, while when attempts have been made to 20 coat standard frames the coating material has filled up the lens receiving groove, thus altering the size and making it no longer standard, and the appearance produced has been unsatisfactory and not practically 25 usable as an ophthalmic mounting. This is due to a considerable degree to the fact that an ophthalmic mounting being worn on the face, comes into line with jewelry and other articles of personal adornment or display, and extreme care must, therefore, be taken 30 in construction of such frames not only that they be of standard size suitable to receive standard lenses which are produced both by the factory and the prescription house, to certain definitely fixed measurements, but 35 in addition the frames must be both durable in finish and neat and attractive in appearance to render them a commercially satisfactory article.

In addition, by the use of the hitherto attempted coating process it has been impossible to produce frames of other than solid color, or in other words, impossible to produce imitation shell or mottled frames, such as are in public demand at the present

time. Furthermore, ordinary dissolved or liquid celluloid will not satisfactorily adhere to smooth or polished metal. This is well recognized in the celluloid art, and while articles have in the past been coated with celluloid, this celluloid will be found to remain satisfactorily in place only so long as there is no loosening action thereagainst, since when loosened it may be peeled off in sheets or strips.

It is, therefore, the purpose of my present 65 invention to provide a novel and improved frame and process of constructing the same by which the frame or mounting may be given any desired color or color combination, in which the metallic effect of ordinarily 70 coated frames may be eliminated and the appearance of a frame covered with sheet or rod material secured, in which the frame shall possess all the advantages, structurally and functionally, of a frame covered 75 with zylonite or other composition in solid form, and at the same time shall be free from all separate fastening devices of any character, in which the entire frame or mounting, or any selected portions thereof, 80 as desired, may be equipped with such coating, and in which the mounting shall when in completed form, be of exact standard size to properly receive standard ophthalmic 85 lenses and securely hold these lenses against any possible twisting or slipping movement.

Many enamels or coatings are brittle and will crack and chip off, and where such a coating is used, for they possess otherwise many advantages of appearance and application, it is an object of my invention to 90 provide a protective coating which will not mar the appearance and which will not chip or crack. This protective coating may be transparent or it may contain color, as desired. Many combinations of color may be 95 made by judicious arrangement of color in each of the two coats and many variations and effects be thus obtained.

Frames for eyeglasses and spectacles are 100 made to fit lenses of predetermined size, known as the "size of eye". The lenses are ground to these standard eye sizes so that they are interchangeable in the frame. If this were not so each lens would have to be 105 ground separately and specially to fit any particular frame. It is, therefore, of the first importance that the frame be made ac-

curately to size in its lens receiving parts and it is an object of my invention to produce a combination frame of metal and non-metallic material in which the lens receiving part is made accurately to size, which hitherto has been impossible in the so-called coated frames.

Other objects and advantages of my improved construction and process of producing same should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a front view of a completed frame embodying my improvements.

Figs. II, III and IV illustrate certain steps in my process.

Figs. V, VI and VII illustrate enlarged detail views further illustrating my invention.

Figure VIII illustrates a final step in my process.

Figure IX represents a sectional view as on the line IX-IX of Figure VIII.

Referring particularly to my improved process of production of combination metallic and non-metallic mountings and my improved frame or mounting as thus produced, I have illustrated in connection with Figure II the initial formation of a metallic rim, which rim is designed to be coated or covered with a non-metallic material in a permanent manner. It is quite essential that the final interior diameter of the frame shall be of an exact standard size and I, therefore, prefer to start with a frame which is itself of a predetermined size. To attain this result I place within the groove of the metal frame 1 the sizer plate 2, which may be designed to produce a 40 millimeter eye, for example, the diameter of the sizer plate being shown as of 41 $\frac{1}{2}$ millimeters, and the frame being gripped on the end pieces 3 by the stretcher jaws 4 to stretch the frame to exactly fit the 41 $\frac{1}{2}$ millimeter plate, the eye wire being thus stretched with this additional size to allow for subsequent filling up of the lens receiving groove by the coating material so that the final size will be the exact 40 millimeter diameter required.

It will be understood that while I have illustrated my invention in connection with the eye wire portion of an ophthalmic frame, it is not limited to this particular type of construction but is capable of use for coating of bridges, guards, end pieces, temples or any other portion of an ophthalmic mounting, the reason for illustrating it in connection with a frame being that certain difficulties present themselves in connection

with the coating of a frame which are not present in connection with other portions of a mounting, and I have, therefore, illustrated and described the most difficult form in my patent, it being understood that it may be used for any of the simpler forms as desired.

In the coating of the frame I may either apply the material to all portions of the frame, or may prefer that certain portions, as for example the end pieces, outer face of the bridge or entire bridge, be free from such coating. If desired to preserve certain portions from the coating they are preferably blanked off, as by the application of a protecting coating of grease, collodion or other suitable film 5, to the parts, which will prevent the coating material from adhering thereto, but which may be readily removed when the operation is completed. The desired parts having been thus protected I preferably proceed with the production of my frame by suitably coating the eye wire, temple, or other part with a layer or film 6 of a suitable metal enamel lacquer or the like, which will firmly adhere to the metal parts. This may be applied by dipping, by the spray device 7; this may be a coating requiring baking to fix it in place, an air drying coating, or the like. It may be a coating of a single color or of more than one color applied separately or consecutively, that is to say, a single entire coating may be applied, allowed to dry and patches of a different color applied, or different parts may be applied during the one operation. The different colors produce a mottled effect, as for instance, the red and brown portions 8 and 9 indicated in connection with Figure IV. Also, the enamel or lacquer may be so applied as to produce a smooth finish surface, as shown in Figure VI, or may be so applied and treated as to produce a rough surface, as shown in Figure V. I find this rough surface particularly advantageous in securing adherence of the subsequent liquid celluloid or the like thereto.

In some instances a smooth surface may be improved by the application of a thin coat of glue, sizing or the like, 10 thereover. The material having been thus suitably built up, I apply, as by dipping, one or more thick coats of liquid celluloid 11 to build up, give body and final finished appearance to the frame. I particularly refer to the application of this by dipping as I have found best results accomplished in this manner, although the material is capable of application by brush, air spray, or the like, if preferred. Also, this coat may be applied of a clear transparent material which will allow the underlying enamel or lacquer coats to show through clearly, but with a glossy appearance due to the presence of the celluloid 130

or the celluloid-zylonite or similar material may have a color of itself to combine with that already on the frame, or a sufficiently deep color to conceal to a great degree that 5 which has been previously applied, this being regulated entirely by the desire of the manufacturer and the particular result which he wishes to accomplish. In any event, however, the ultimate result is the same, in that 10 a novel and improved construction is the result of my process, which construction has an initial coat firmly gripping and engaging the metal and forming a foundation for the subsequent non-metallic material built up 15 thereon in heavy body form and with such color and markings as are desired.

I would call particular attention to the fact that by my improved process it is possible to produce attractive and desirable 20 ophthalmic mountings and fittings therefor which shall be mottled in imitation of shell or in any desired way, a result impossible of accomplishment by previously known dipping processes for coating of ophthalmic 25 mountings.

As a final step in the completion of my improved process and to produce a commercially practical frame, something not hitherto produced through dipping, I place 30 the coated frame about the former 12 which has its exterior diameter exactly correct and is preferably interiorly heated as by the coil 13. The frame is then again stretched around this former 12 through the use of the 35 jaws 4, as in the initial step of my process, the heated former softening the covering composition within the groove and allowing the frame to come down around the former when the groove will be the exact diameter 40 and of exact circumferential measurement necessary to properly fit a standard lens and eliminate any possibility of the lens twisting or turning when mounted within the frame. It will be apparent that when the 45 above operation is carried out the excess material will be pressed outwardly thus eliminating a portion of the coating material in the groove of the eye wire.

In those cases where the enamel layer is 50 of a brittle or frangible nature it may be readily seen that the coating of tough, elastic, celluloid will form a protective coating, preventing the enamel from chipping off and at the same time maintaining the luster and 55 sheen of the highly polished surface.

I claim:

1. The process of forming a combination metallic frame consisting in forming a metallic frame with a lens receiving groove, 60 coating the frame with a non-metallic material, and subsequently removing the ma-

terial from the groove of the frame to form a lens receiving groove of standard dimensions.

2. The process of producing a composition 65 ophthalmic mounting consisting in forming an eye wire with an interior groove, building up a composition coating on the eye wire and producing a standard size lens receiving groove in the frame by eliminating 70 a portion of the coating within the groove.

3. The process of making a lens receiving frame for an ophthalmic mounting comprising making a metallic frame section with an interior groove, building up a composition 75 covering on the metallic frame section and producing a standard size lens receiving groove in the frame by eliminating a portion of the coating within the groove of the metallic frame.

4. The process of forming a combination metallic frame consisting in coating a metallic frame with a heat softenable non-metallic material and stretching the combined frame around a heated size plate whereby 85 the non-metallic material is displaced by the size plate to produce a standard size lens-receiving groove.

5. The process of forming a lens receiving frame for ophthalmic purposes, consisting 90 in constructing an ophthalmic mounting, stretching the eye wire to predetermined over-size, applying a metal engaging enamel to the eye wire, applying a sizing to the enamel, building up a composition covering 95 around the sizing, and stretching the built-up eye wire about a heated standard eye size plate to displace a portion of the outer coating, and form a standard size lens receiving groove within the eye wire.

6. As an article of manufacture, an ophthalmic mounting including a metal base member and a built-up composition covering therefor having a lens receiving groove of standard size, said composition covering 105 being displaced at the groove to produce the necessary standard measurements at this point.

7. The process of making a lens-receiving frame for an ophthalmic mounting comprising making a metallic frame section slightly larger than the size of lens to be fitted therein, covering the frame section with a non-metallic coating and shaping the coating over a former of the exact lens size.

In testimony whereof, I have affixed my signature in presence of two witnesses.

ELMER L. SCHUMACHER.
